UNITED STATES PATENT OFFICE.

FREDERIC E. IVES, OF PHILADELPHIA, PENNSYLVANIA.

PHOTOGRAVURE-PRINTING PLATE.

SPECIFICATION forming part of Letters Patent No. 495,341, dated April 11, 1893.

Application filed August 4, 1891. Serial No. 401,676. (No model.)

To all whom it may concern:

Be it known that I, FREDERIC E. IVES, a citizen of the United States and a resident of Philadelphia, Pennsylvania, have invented a certain Improvement in Photogravure-Printing Plates, of which the following is a specification.

The object of my invention is to produce an intaglio photogravure or phototype printing plate having in the deep shades a surface which will act effectively to retain the ink during the cleaning of the plate, and this object I attain in the manner hereinafter set forth, reference being had to the accompanying drawings, in which—

Figure 1, is a view of part of an intaglio printing plate made in accordance with my invention showing the plate as it appears after having been inked and cleaned, ready to print; and Fig. 2, is an exaggerated section of the plate.

In ordinary photogravure or phototype printing in which the printing plate is in the form of an intaglio and in which the lights and shades of the picture are made up of regularly spaced lines or dots graduated in size according to the shades of the picture, said lines or dots meet or merge in those portions of the plate representing the blacks or deep shades of the original, hence the surfaces of these portions of the plate are entirely removed by the etching process, and spaces of comparatively large area are formed without any raised lines or dots therein, and in cleaning the face of the plate, after the inking of the same, and preparatory to printing, the ink is likely to be withdrawn from these spaces owing to the lack of any retaining projections therein, so that, in the deep shades of the picture the printing is frequently of a spotted or irregular character, this being especially the case where the printing is effected on power presses in which that careful cleaning of the plate resorted to in hand printing is impossible. Attempts have been made to overcome this objection, by mechanical roughening of the sunken portions of the printing plate so as to provide in these portions a surface to hold the ink, but this operation, besides be-

ing a tedious and comparatively expensive one, is not properly effective for the purpose.

In carrying out my invention, therefore, I so make the photographic positive from which the usual etched printing plate is to be produced that the lines or dots will extend throughout the deepest shades of the picture, as shown for instance in Fig. 1 of the accompanying drawings, so that the etched printing plate produced from such a positive will have in the sunken portions representing even the darkest shades of the picture a series of fine lines or projections, as shown for instance at *a* in Fig. 2, so that they will serve as an effectual means of retaining the ink in these portions of the plate, and will insure a solid and uniform printing of the deep shades of the picture. These lines or dots may extend to the face of the plate, in which case the light lines or dots will extend throughout the deeply shaded portions of the picture, without, however, assuming such prominence therein as to materially modify the deep tones of such parts, or the lines or dots may be slightly reduced in height by the process of chemical etching without materially affecting their function as ink retainers.

A photographic positive of the character described can be produced in various ways, and hence my invention is not limited to the specific means of making such a positive.

In carrying out that process in which the body shades of the original are translated into lines or dots by the interposition of a regular pattern of lines or dots in the camera, the exposure may be short enough to leave the lines or dots open to a slight extent in the deepest shades of the picture or in producing a plate, in accordance with my patent of February 8, 1881, No. 237,664, or August 9, 1881, No. 245,501, the pressure imparted to the lined or stippled plate may not be sufficient to completely flatten, or run together, the raised lines or dots in those portions representing the deep shades of the picture.

Having thus described my invention, I claim and desire to secure by Letters Patent—

An intaglio photogravure printing plate in

which the light and shade of the picture are made up of regularly spaced lines or dots graduated in size to accord with the shades of the picture, but continued throughout the deepest shades so as to serve as ink retainers in those portions of the plate, substantially as specified.

In testimony whereof I have signed my name to this specification in the presence of two subscribing witnesses.

FREDERIC E. IVES.
